UNITED STATES PATENT OFFICE.

FRANK C. ANDERSON, OF CINCINNATI, OHIO, ASSIGNOR TO THE AMERICAN VALVE AND METER COMPANY, OF CINCINNATI, OHIO, A CORPORATION OF OHIO.

SWITCH-INTERLOCKING DEVICE.

Application filed May 29, 1926. Serial No. 112,597.

My invention relates to switch-stands and interlocking devices for use therewith, and is an improvement upon such devices as are disclosed and claimed in my prior Patents No. 5 1,547,010 of July 21, 1925, and Nos. 1,554,543, 1,554,544 and 1,554,545 of September 22, 1925; having as its object, in common with those prior inventions, the locking of the interlocking mechanism by a manually applied lock, and having the further object of 10 coordinating the interlocking device with the switch-stand latch, so that locking of either one also locks the other and so that neither can be locked unless the switch rails are in 15 safe position. Other objects will appear in the course of the ensuing description.

I attain these objects by the device illustrated, for example, in the accompanying drawings, in which—

20 Figure 1 is a general perspective view of part of a switch and a switch-stand connected thereto and equipped with my improved device;

Fig. 2 is an enlarged rear perspective view 25 of the device, together with the latch;

Fig. 3 is a detail perspective view of the base;

Fig. 4 is a similar view of the plunger;

Fig. 5 is a plan view of the device, partly 30 in section on the plane of the line 5—5 of Fig. 6;

Fig. 6 is a vertical longitudinal section on the plane of the line 6—6 of Fig. 5; and

Fig. 7 is a detail perspective view of the 35 lever.

As usual in interlocking installations, the interlocking bar 1 has the threaded part 2 secured in the bent down plate 3 fixed to the end of the point rail 4 by nuts 5 and extending under the stock rail 6 out to one side 40 of the track. My present device is especially adapted for use with the type of switch-stand shown in Fig. 1, comprising a casing 7 with the vertical target shaft 8 journaled 45 therein, carrying the crank 9 on its lower end below the casing. This crank 9 is connected to the two point rails 4 and 4' by the rods 10 and 11 as usual; and the top of the shaft carries the target 12 above the casing 50 7. The hand lever 13 connects with suitable mechanism, inside the casing 7, so that swung one hundred and eighty degrees in a vertical plane, it rotates the shaft 8 and crank 9 ninety degrees to throw the switch.

55 To hold the lever 13 down and hold the

switch in closed position, a latch of well known construction is provided, comprising the frame 15 with a crotch receiving the lever, and a keeper 16 pivoted in the lower end of the frame and swinging in over the 60 lever behind an opening 17 in an ear on the upper part of the frame, if the lever 13 is fully down in the crotch, but covering the opening 17 otherwise, so that a padlock 17' may be inserted in the opening 17 only when 65 the switch is closed. The lower part of the keeper has the treadle 18 extending out; and when this latch is used without the interlocking device, the switchman applies his foot to this treadle 18 to open the latch. A 70 similar latch, part only of the frame 15' thereof being shown, receives the lever when the switch is thrown to opposite position; these latches being fixed to the head blocks 19 and 19', respectively, which support the 75 switch-stand (Fig. 1).

The interlocking bar 1 extends along the head block 19 some distance below the top thereof, at the front side thereof, out past the switch stand and latch, with its outer 80 end part of rectangular cross-section, having its narrow edges horizontal. The interlock housing comprises a base 20 and a casing 21. The base 20 is mainly a flat plate lying across the top of the head block 19 and having a stirrup 22 depending in front of the head block, with a transverse rectangular opening 22' in which the bar 1 has a sliding fit. From its top down to the bar 1 the base 20 has a circular opening 20' in which the 85 interlocking plunger 23 slides up and down, with its lower end engaging in a notch 24 in the upper edge of the bar 1 when the plunger is down. This plunger 23 has its upper end in the form of a head with a pin 25 transversely through it; and the operating lever 26, fulcrumed on a transverse pin 27 in lugs 28 upstanding from the base 20 and straddling the lever, has a fork 29 straddling the head of the plunger 23, with holes 30 in 90 which the projecting parts of the pin 25 engage.

The base 20 has a part 31 overhanging the stirrup 22 forwardly, and has a slot 32 from the plunger opening 20' out through its front 105 edge, in which the plunger 23 has a forwardly extending ear 33 with an opening 33' transversely through it. When the plunger 23 is down in the bar notch 24 this opening 33' is just below the overhanging part 31 of 110

the base 20, so that if the padlock 34 is inserted in the opening 33' it engages with the bottom of the base part 31, preventing raising of the plunger out of the notch 24. 5 When the plunger is raised out of the bar notch 24 this opening 33' is carried above the base.

The rear end of the lever 26 is in the form of a treadle 35, on which the switchman may 10 place his foot to depress this end of the lever to raise the plunger 23 and release the bar 1, so that the switch may then be thrown by operation of the switch-stand in the usual manner as before described. The casing 21 is a 15 box-like element, with its bottom open, fitting down over the lever 26 and plunger 23, with its lower front edge 36 and lateral lower edges 37 and lower rear edge 38 resting on the base 20 along the corresponding edges of 20 the base, which has lateral ears 39 with which the housing or casing 21 has lateral ears 40 registering, so that screws 41 passed down through the casing ears 40 and the base ears 39 into the head block 19 may hold the 25 casing to the base, and both of them to the head block. Also, the base 20 has the rear ear 42 through which a third screw 41' may be passed into the head block. Near its front end the base 20 has the small lugs 43 projecting up at its sides, to flank the casing edges 37 closely, cooperating with the side screws 41 in holding the casing 21 from sidewise twisting. The lever fulcrum lugs 28 are near the rear end of the base and casing, and the 30 latter has the vertical slot 43' in its rear end, out through which the rear arm of the lever 26 extends, to swing up and down therein. To force the front arm of the lever 26, and the plunger 23 therewith, downward, a helical 35 spring 44 fits around a lug 45 on the top of the lever near the fork 29 thereof, and is compressed up against the under surface of the top of the casing 21.

The rear arm of the lever 26 curves upward outside the casing slot 43', and has under its treadle 35 the vertical web 46 with a rearwardly opening slot 47 receiving the adjacent edge of the latch treadle 18, so that depression of the interlock treadle 35 to open the interlocking device also opens the latch by depression of the latch treadle 18; and, as the interlocking device closes, under action of gravity aided by the spring 44, raising the 40 rear arm of the lever 26, the latch is closed by raising of its treadle 18. If the switch-throwing lever 13 is not completely down in the latch crotch, the latch cannot close, and neither can the interlocking plunger go completely down; or, if the plunger cannot enter 45 the bar notch 24 because the point rail is not completely drawn up to the stock rail, the interlocking device cannot completely close and neither can the latch be closed. Therefore, although there are two places, in either 50 one of which a padlock may be applied, the

interlocking plunger ear opening 33' and the latch ear opening 17, the lock cannot be applied to either one unless both the switch-stand and the interlocking device are completely closed, with a corresponding safe position of the rails of the switch. 70

I prefer to lock the switch by application of the lock to the plunger opening 33' as shown in Fig. 6, because the lock thus is down below the top of the head block 19, 75 where it is better protected against accidents, and even should the upper part of the interlocking device, above the top of the head block, be disrupted, the plunger, directly locked, is less liable to be dislodged from its 80 engagement in the bar 1, so that it will hold the point rail in safe position in that event. However, application of the lock to the latch opening 17 is more convenient for the switchman, and this may be done when preferred, 85 still availing of the protection of the interlocking against locking the point rail in unsafe position on account of the operative connection of the treadles of the two devices. I prefer to have the slot in the interlock treadle 90 web with the latch treadle engaged in it, as shown and described, because it is more convenient to extend the interlock lever arm upward than to change the latch treadle in this 95 way; but it is obvious that the relation may be reversed, with the latch treadle having the slot in a web thereunder, and receiving the edge of the interlock treadle. Or, one of the elements may have the treadle part omitted, merely being a lever; but by providing 100 both devices with treadles, either one is complete for use alone, without the other, as may be desired. For example, the interlocking device may be used with other types of 105 switch-stands which do not have latches down on the head blocks; and of course where a stand of the type shown is installed without the interlocking device, it nevertheless would require latches. 110

It will be evident therefore that numerous modifications may occur, and while I have specifically disclosed a certain preferred example of my invention, I do not wish to be understood as being limited to such precise disclosure, but having thus fully described 115 my invention, as is required, what I claim as new and desire to secure by Letters Patent is:

1. A switch-interlocking device comprising an interlocking bar and a plunger reten- 120 tively engaging said bar at one side of the switch head block, locking means on said plunger below the top of the head block, and a lever connected to said plunger and extending along the track from said plunger, across the head block, and latch-engaging means on said lever near the opposite side of the head block. 125

2. A switch-interlocking device comprising an interlocking bar and a plunger reten- 130

tively engaging said bar at one side of the switch head block, locking means on said plunger below the top of the head block, and a lever connected to said plunger and extending along the track from said plunger, across the head block, and a treadle on said lever near the opposite side of the head block.

3. A switch-interlocking device comprising an interlocking bar and a plunger retentively engaging said bar at one side of the switch head block, and a lever connected to said plunger and extending across said head block, a treadle on said lever near the opposite side of the head block, latch-engaging means on said lever under said treadle.

4. A switch-interlocking device comprising an interlocking bar and mechanism comprising a vertically moving plunger at one end, retentively engaging said bar, said mechanism extending along the track, across the switch head block, from said bar, and locking means for said mechanism on said plunger below the top of the head block.

5. A switch-interlocking device comprising an interlocking bar having a notch in its upper side, and mechanism comprising a vertically moving plunger engaging in said notch, and means on said plunger for applying a padlock thereto.

6. A switch-interlocking device comprising a base with a stirrup depending therefrom, a bar sliding in said stirrup and having an upwardly opening recess, a plunger sliding down in said base into said recess, and locking means on said plunger adjacent to said stirrup and below the top of the base.

7. A switch-interlocking device comprising a base made up of a base plate to lie over the head block and a stirrup to depend alongside the head block, a bar sliding in said stirrup and having an upwardly opening recess, a plunger sliding down in said base into said recess, said base plate overhanging said stirrup and having a slot, and an ear on said plunger having a lock-receiving opening, below said overhanging part of the base plate when the plunger is in the recess but above the lower side of said overhanging part, so as to prevent insertion of

the lock, when said plunger is out of said recess.

8. In a switch-interlocking device, a base comprising a plate with an integral depending stirrup having a transverse opening and an upright plunger-receiving opening, and an integral lever-fulcrum lug upstanding on said base.

9. In a switch-interlocking device, a base comprising a plate with a depending stirrup having a transverse opening and an upright plunger-receiving opening, and having a slot in its plate opening out from said upright opening.

10. In a switch-interlocking device, a base having means on its top for mounting interlocking mechanism and having laterally extended ears on its lateral edges, and a casing fitting down on said base around said mounting means and having ears registering with said base ears.

11. In a switch-interlocking device, a base, a bar sliding horizontally in said base, a plunger sliding up and down in said base to engage with said bar, a lever fulcrumed on said base and connected to said plunger, a casing fitting on said base over and around said lever, and a spring confined between said lever and the under side of the top of said casing, to force the plunger downward.

12. In a switch-interlocking device, a lever having a fork at one end, fulcrum means near its middle, a treadle and a latch-engaging means near its opposite end, and a spring-holding lug between its fulcrum means and its fork.

13. In a switch-interlocking device, an operating lever having a treadle on one end with a vertical web thereunder having an outwardly opening slot in which part of a switch-stand latch is adapted to be engaged.

14. In combination, a switch-interlocking device and a switch-stand latch, each having lock-receiving means, and an operative connection between said device and said latch whereby they open or close together, said device and said latch each having a treadle, whereby either one is adapted for manual operation alone, without the other.

FRANK C. ANDERSON.
